UNITED STATES PATENT OFFICE.

FRED WUNDERLY, OF NAZARETH, PENNSYLVANIA, ASSIGNOR TO ROBERT MEYER AND WILLIAM C. FOULDS, OF PHILADELPHIA, PENNSYLVANIA.

HOSIERY-SINGEING MACHINE.

SPECIFICATION forming part of Letters Patent No. 641,618, dated January 16, 1900.

Application filed April 6, 1899. Serial No. 712,010. (No model.)

To all whom it may concern:

Be it known that I, FRED WUNDERLY, a citizen of the United States, residing at Nazareth, in the county of Northampton and State 5 of Pennsylvania, have invented certain new and useful Improvements in Machines for Singeing Stockings; and I do hereby declare the following to be a full, clear, and exact description of the invention, such as will enable 10 others skilled in the art to which it appertains to make and use the same.

My present invention relates to certain new and useful improvements in singeing-machines, and more particularly to machines 15 for singeing hosiery to remove the fine "fly" or "fuzz" therefrom, so as to give to the articles a high grade of finish.

One object of the invention is to provide a simple machine comprising a comparatively 20 small number of operating parts and one easy to operate and not likely to get out of order.

A further and important object of the invention is to provide a machine so constructed and arranged as to singe both sides of the 25 stocking at once, thereby adding greatly to the capacity of the machine, and consequently reducing the cost of the singeing operation.

Briefly and specifically stated, the invention 30 comprises a suitable bed-frame carrying feed and delivery tables arranged at opposite ends thereof, two pairs of feeding-rollers, with mechanism for operating them, and a pair of burner-tubes located intermediate 35 the said feed-rollers and arranged in close proximity to each other, but preferably out of a vertical line, said burners being constructed to throw their flames outward at an angle and preferably toward each other, so 40 as to act upon and singe both sides of the stocking at one operation as they are fed between the burners by the feed-rollers.

The invention comprises other novel features of construction and details of parts to 45 be hereinafter more definitely described, and then particularly pointed out in the claims which conclude this specification.

In order to enable others skilled in the art to make and use my said invention, I will

proceed to describe the same in detail, reference being had for this purpose to the accompanying drawings, in which—

Figure 1 is a longitudinal sectional view of a machine constructed in accordance with my invention. Fig. 2 is a longitudinal side 55 elevation of the same. Fig. 3 is a top plan view. Fig. 4 is a detail view of my improved form-of burners. Fig. 5 is a plan view of the board or former over which the stockings are stripped when passed through the 60 machine.

Referring now to the drawings, the reference-numeral 1 designates the base or bed frame of the machine, which is preferably made of cast-iron, and upon opposite sides 65 of this frame, at each end thereof, are bolted wooden supports 2, which extend outward therefrom, as shown, and upon these supports rest the feeding-table 3 and receiving-table 4, respectively. Journaled in suitable 70 bearings in the said base-frame are two lower shafts 5, each carrying a gear 6 at one end, and intermediate said gears is a stub-axle 7, carrying an intermediate gear 8, which meshes with the said gears 6 to transmit power from 75 one to the other, whereby they will be rotated in unison. Power is applied to one of the shafts 5 through a belt (not shown) passed over a pulley 9, fixed to the outer end of one of the shafts 5. By preference I arrange a 80 loose pulley 10 adjacent to the pulley 9 on the shaft 5, so that the said belt may be shifted from one pulley to the other in order to operate the gears or allow them to remain at rest, as will be obvious.

Arranged directly above each shaft 5 is another or upper pair of shafts 12, which latter are journaled in slotted bearings 13, formed by upward extensions 14 of the said base-frame, and to the outer end of each of said 90 shafts 12 is fixed a gear-wheel 14', which gear-wheels mesh with the said gears 6 on the lower shafts 5. Each of the shafts 5 and 12 carries a hollow metal feeding-roller 15, which is fixed to its respective shaft so as to rotate 95 therewith. The rollers of each pair are nearly in contact with each other, as will be seen, and this point of peripheral contact of the

rollers is on a line or level with the feeding and receiving tables 3 and 4, for a purpose presently to appear.

Between the upper pair of shafts 12, at one side of the machine, the bed-frame is formed with an extension 16, provided with two apertures to receive and support the burner-tubes now to be explained.

The burners consist of a main tube 17, which

- 10 leads from some suitable source of supply, as a vaporizer 18, and passes through one of the apertures in the extension 16 and extends transversely across the machine, as shown. One side of said tube near the bottom there-
- 15 of is provided with a plurality of fine jet-openings 19, preferably arranged in rows, the said openings being so disposed as to shoot a flame therefrom in an upwardly-inclined direction. Arranged parallel to the said main
- 20 tube 17 and in close proximity thereto is a second or branch tube 20, which latter is located above and preferably slightly in rear of the said main tube—that is, slightly out of a vertical line—and this tube also passes
- 25 through an opening in the extension 16 of the bed-frame and joins the main tube 17 at a point 21 outside the frame, as clearly shown in Fig. 3. This branch tube is likewise provided with fine jet-openings 22; but these
- 30 openings are disposed at one side thereof near the bottom of the tube, so as to conduct its flame in a downward-inclined direction toward the flame of the upper tube; but it will be noted that in view of the fact that the
- 35 lower tube is located in advance of the upper tube the flames are not directed to a common point, and there will therefore be no danger of the flames uniting, which might result in burning or scorching the articles passed between them. By preference I make the jet-
- 40 openings 19 in the lower tube considerably smaller than those in the upper tube, so that the flame formed by this lower tube will be only about one-half the size of that formed
- 45 by the upper tube; but although the flame is smaller its heat will be equally as intense, owing to its natural tendency to travel in an upward direction.

By arranging the two burner-tubes in close proximity to each other and having their flames directed upward and downward, respectively, it will be seen that should an article, such as a stocking, be passed between the flame all the long surplus fibers or fly

55 will be closely singed therefrom at one and the same operation, and this I consider to be an important desideratum in this class of singeing-machines, as it saves considerable time and labor, and consequently greatly reduces the cost of the singeing operation.

The feeding-table 3 is provided with two parallel guides 23, as shown, so located in a direct line with the feed-rollers as to cause the stockings and their former or stripper board 24 to pass evenly and squarely between the said feed-rollers and burners.

The operation of the machine will be readily understood from the foregoing description and following brief statement: The stockings to be treated or singed are first stripped upon the boards or formers 24, whereby they are stretched or distended, and the machine being set in motion so as to rotate the feed-rollers in the direction of the arrow, Fig. 1, the said formers and their stockings are placed between the guides 23 on the feeding-table and pushed forward until gripped by the first set of feeding-rollers. The upper rollers being mounted in slide-bearings or U-shaped slots are allowed a sufficient vertical movement to compensate for the thickness of the former-board and surrounding stocking and do not therefore mash or unduly press the latter, but only grip them with sufficient force to cause a forward feed between the 85 burners and flames where the superfluous fibers are singed away, and they are then caught by the second set of rollers and delivered in a finished condition upon the delivery or receiving table 4, from whence they are removed, as desired.

By stripping the stockings to be singed over a "former," such as 24, which is somewhat larger than the stocking, it will be seen that the latter will be stretched or distended 95 in all directions, so that the threads are abnormally separated or pulled apart, and by this operation the jets of flame can act upon all parts of the stocking to more effectually perform the singeing operation. This is especially advantageous in singeing what are known as "ribbed" stockings. Furthermore, it will be seen that by the use of the former the stockings will be supported in a practically rigid condition during the feeding and 100 singeing operation. Thus I am enabled to dispense with other supporting means for the stockings during their passage through the machine. It will also be observed that the former when placed within the stocking will 110 prevent the two jets of flame from uniting during the passage of the former and surrounding stocking between the said jets. Thus there will be no danger of burning or scorching the stocking during the singeing operation, the former in this case acting as a barrier to the flames and keeping them from 115 uniting.

It will be seen that the machine is very compact and comprises only a very few operating parts, and these are so constructed and arranged that there is little likelihood of their ever getting out of order. In the drawings I have shown the burners as being supplied with gas from a hydrocarbon-generator; 125 but I do not wish to be limited to such, for obviously any form of gas-supply may be employed.

While I have stated that by preference the gas-exit openings in the lower burner-tube 130 will be made smaller than the openings in the upper tube, still I do not wish to confine

in myself to this arrangement, for it will be obvious that I may bring about the same result by making the openings in both tubes of the same size and simply reduce the size of the opening in the gas-entrance end of the lower burner-tube, which would result in supplying a less quantity of gas to this tube, and consequently reduce the size of the flame.

I have heretofore stated that the rollers 15 are made hollow, and I consider this to be very important, for the reason that they will thus be kept practically cool, which would not be the case if they were solid. These rollers are arranged in quite close proximity 15 to the burners and would become extremely hot if they were not provided with end openings to admit the external atmosphere for ventilating purposes. Furthermore, the rollers are comparatively large in size, and will 20 thus afford a better grip upon the articles and give a more uniform feed. In the practical embodiment of my machine the two pairs of rollers are arranged in quite close relation to each other, so that short as well as long stockings 25 can be passed between them with facility and good effect.

What I claim, and desire to secure by Letters Patent, is—

1. In a singeing-machine, a pair of burners located in close proximity to each other and each provided with jet-openings arranged to produce an upward and a downward disposed flame, respectively, a feeding-table at one end of the machine and a receiving-table at 35 the other end, and means for causing the article to be singed to travel from the feeding-table, between the burners, and to be delivered onto the receiving-table.

2. In a stocking-singeing machine, a pair 40 of burners located in different planes and each having jet-openings therein arranged to direct their flames in an upward and a downward direction, respectively, a feeding-table at one end of the machine and a receiving-table 45 at the other end, and feed-rollers arranged adjacent to the said burners and adapted to conduct the stockings to be singed, from

the feeding-table, between the burners and deliver them onto the receiving-table.

3. In a stocking-singeing machine, the combination with the bed-frame, of a table arranged at each end thereof, two pairs of feed-rollers journaled in bearings on said bed-frame, a train of gears connecting said rollers to rotate them in unison, and a suitable 50 burner or burners located intermediate the said feed-rollers, out of a line taken horizontally along the level of the said tables.

4. In a stocking-singeing machine, the combination with the bed-frame, of a table arranged at each end thereof, two pairs of feed-rollers journaled in bearings on said frame, a train of gears connecting said rollers to cause them to rotate in unison, and a pair of 60 burner-tubes located intermediate the said 65 feed-rollers, and each provided with jet-openings arranged to produce an upward and a downward flame, respectively, the parts coöperating, substantially as described.

5. In a stocking-singeing machine, the combination with the bed-frame, of a table arranged at each end thereof, a pair of lower feed-rollers, a pair of upper feed-rollers arranged above the said lower rollers, the adjacent peripheries of said rollers being on a 70 level with the said tables, means for causing 75 said rollers to rotate in unison, a main burner-tube supported by an extension on the said bed-frame and arranged between the feed-rollers on a line slightly below the level of 80 the tables and a branch burner-tube arranged parallel with the said main tube, but slightly above the same and above the level of the tables, said burner-tubes being provided with 85 jet-openings so disposed as to produce an upward and a downward flame, respectively, substantially as described.

In testimony whereof I affix my signature in presence of two witnesses.

FRED WUNDERLY.
